UNITED STATES PATENT OFFICE

2,104,127

AIR DRAFT AND SMOKE CONSUMER

William B. Hickman, Kansas City, Mo.

Application June 22, 1936. Serial No. 86,488

2 Claims. (Cl. 126—58)

The present invention relates to heating apparatus, and aims to provide an improved heater or stove construction for more efficient combustion of the fuel used, as well as for a more effective operation of such apparatus for room-heating purposes.

Accordingly I have devised a heater construction in which an improved draft provision is made for the supply of the necessary air for supporting combustion, wherein such air is supplied not only at the most efficient points for combustion purposes, but is admitted evenly or uniformly to all parts of the combustion zone.

The improved construction further comprises an efficient means for retarding the movement of the gases and fumes from the combustion zone for the purpose of effecting a more nearly complete combustion, and also of retaining the hot products of combustion within the heater body for a longer period, and thereby prolonging the room-heating effect of the apparatus. The construction which I have devised for this retarding means comprises preferably a movable portion, and a further feature of the invention is the provision of means operated by the opening of the feed door for fueling purposes, to effect automatically such change of the position of said movable portion of the retarding means as will afford ample room or clearance for this fueling operation.

With the foregoing general objects in view the invention will now be described by reference to the accompanying drawing illustrating one form of construction which I have devised for embodying the proposed improvement, after which those features and combinations deemed to be novel and patentable will be particularly set forth and claimed.

In the drawing—

Figure 1 is a vertical sectional view illustrating an apparatus constructed in accordance with my invention;

Figure 2 is a horizontal sectional view, representing a section taken on the line 2—2 of Figure 1; and

Figure 3 is a vertical sectional view, representing a section taken on the line 3—3 of Figure 1.

Referring now to the drawing in detail, the improved construction is illustrated therein as comprising a base member 5 for the ash pit and provided with a door 6 for access thereto and removal of the ash pan 7 (see Figure 1). Over the base member 5 is mounted a fire pot member 8 providing a chamber 10 for the fuel and

containing the grate structure 12 at the bottom of said chamber. The top rim of the fire pot member is formed with a marginal flange 14 surrounding a seat 15 for supporting a heating drum 16 forming the stove body and having the top portion 17 provided with a flue outlet 18, as shown in Figure 1. The bottom portion of the drum 16 is perforated to provide a series of air-inlet openings 20,—see Figures 1 and 3.

The lower front portion of the drum or stove body 16 is formed with a door opening 21 provided with a hinged door 22, for the supply of fuel to the chamber 10, and within the lower portion of said drum, that is, opposite said door 22, I provide a downwardly tapered or inverted-cone-shaped deflector structure comprising two segments 24 of approximately equal size bolted together as indicated at 25, and a third segment 26 carried by a pivot pin or bolt 27 secured to the lower edge of said segment 26 and mounted in bearing lugs 28 near the lower ends of the segments 24.

The lower portion of the deflector is substantially ring-shaped as indicated at 29, and the sectional structure of the deflector member permits it to be readily assembled within the drum where the deflector is secured by means of bolts or the like 30, whereby its upper flange margin 21 is attached to the interior of the drum.

The pivoted segment 26 is sufficiently wide to overlap the adjacent edges of the segments 24, and the pivotal mounting of the segment 26 is for the purpose of providing ample clearance for the feeding of fuel through the opening 21 into the fire chamber 10. Accordingly I provide connections between the door 22 and said pivoted segment 26 for causing the latter to automatically swing inward upon its pivot pin 27, whenever the door is opened. These connections comprise a short crank member 33 fixed to the pin 27, and a link 34 formed with loops at its opposite ends for pivotally connecting the link to said crank member and also to a lug 35 projecting inwardly from the inner face of the door 22, as illustrated in Figures 1 and 2.

For the automatic control of the air admitted for draft purposes through the ash pit to the under side of the grate 12, I provide an improved thermostat control comprising a thermostat element 38 connected with one end of a lever 39 which is fulcrumed at 40 and has its other end connected with a draft damper 42 mounted at the side of the base member 5 and controlling the admission of air to the ash pit. For regulating purposes, the several parts of said auto-

matic control are shown as capable of adjustment, the element 38 and lever 39 being each adjustably mounted on supporting rods 44 and held by means of set screws 45, whereas the connection between said lever and the damper 42 is by means of a link 47 having an adjustable screw connection 48 with one end of the lever 39.

With the foregoing construction, the deflector member provides means for trapping the smoke and gases or fumes in the space around and beneath the deflector member, and thus retarding the flow of mingled smoke and fumes until a more complete combustion of the same has been effected and before the continued flow of the products of combustion takes place upward through the outlet provided by the central opening through the ring-shaped lower end 29 of the deflector structure,—all as represented by the arrows shown in Figure 1. While a part of the air supporting combustion is supplied through the base member, an improved method of supplying the necessary air is provided by the series of air intake openings 20 entirely surrounding the fire bowl just above the level of the burning fuel, whereby an even draft is afforded for maintaining uniform combustion at all points of the fire level.

Since the movement of the gases, smoke and other products of combustion is retarded and caused to remain within the zone of highest temperature for that much longer a period, it is apparent that not only does a more complete and efficient combustion take place, but a correspondingly longer period is also afforded for heating purposes and radiation of the heat to the air in the vicinity of the stove before the smoke and fumes can finally escape from the upper portion of the drum by way of the flue outlet 18.

When necessary to add fuel to the fire chamber, the opening of the door 22 operates through the described connections to automatically swing the segment 26 of the deflector inward toward the center of the stove, as represented by the dotted lines in Figure 1, and thus provides ample clearance for the fueling operation, and at the same time prevents any appreciable amount of smoke or fumes from escaping into the room; after which the closing of the door also forces said swinging deflector section to return to its original position as illustrated by the full lines in the drawing.

The thermostatic control structure herein described further provides an efficient method of regulating the draft through the base member to the bottom of the fire bowl, to maintain a uniform operation of the stove. As the temperature falls around the stove, the thermostatic element opens the damper to a greater extent to admit more air, while a rise in temperature produces a corresponding closing movement of said damper, and the several adjustments afforded by

means of the set screws 45 and 48 enable the control to be set to suit the requirements of the particular apparatus and operating conditions.

I have found that with an apparatus as above described, not only is an even heat produced but also that there is a marked efficiency in its combustion operation, producing a light ash and no cinders from an average grade of fuel, from which facts and also the fact that but little smoke results from the operation of the stove it appears that the improved construction is such as to provide a more uniform and effective supply of air for supporting the combustion as well as a greater opportunity for more nearly complete combustion of all the fuel; this in addition to the advantages resulting from the retarding of the escape of the heated products of combustion and thereby prolonging their heating effect upon the surrounding air of the room.

While I have illustrated and described what I now regard as the preferred form of construction for embodying and practicing the invention, it is apparent that various changes are possible within the principle of the same; for example, the improvement may be embodied in a furnace construction as well as in the form of a room heater as shown, with corresponding benefits as regards efficiency of operation. I therefore desire to be understood as reserving the right to make such changes and modifications as may fairly fall within the spirit and scope of the appended claims.

What I claim and desire to secure by Letters Patent is:

1. A heater construction comprising a fire chamber, a heater drum mounted over said chamber and provided with a fire door, a deflector member of substantially inverted-cone shape within the lower portion of said drum and having a central opening for the escape of fumes and gases to the upper portion of the drum, said deflector member having a movable section opposite said door, and connections between said door and movable section of the deflector member operated by opening of the door for swinging the section inward away from the door.

2. A heater construction comprising a fire chamber, a heater drum mounted over said chamber and provided with a fire door, a deflector member of substantially inverted-cone shape within the lower portion of said drum and having a central opening for the escape of fumes and gases to the upper portion of the drum, said deflector member having a movable section mounted opposite said door upon a pivot adjacent said central opening, and connections between said door and movable section operated by opening of the door for swinging said deflector section inward away from said door.
